UNITED STATES PATENT OFFICE.

ALBERT H. SANDSTROM, OF PORTLAND, OREGON, ASSIGNOR OF ONE-FOURTH TO P. M. HALL-LEWIS AND ONE-FOURTH TO E. W. HANSEN, BOTH OF PORTLAND, OREGON.

FIREPLACE LINING.

Application filed August 24, 1922. Serial No. 584,059.

To all whom it may concern:

Be it known that I, ALBERT H. SANDSTROM, a citizen of the United States, and a resident of Portland, county of Multnomah and State of Oregon, have invented a new and useful Fireplace Lining, of which the following is a specification.

The present invention relates to improvements in fireplace linings and has particular reference to a metal lining for fireplaces composed of preferably four sections that may be easily assembled even by a layman and it will at the same time assist in the construction of the fireplace due to the fact that it conforms to the outlines of a well constructed fireplace and thus forms a guide for the builder. A particular feature of the invention is that the sections are so constructed that the main sections are substantially adapted to be used for any size of fireplace while auxiliary sections are provided which may be sold in the market in varying sizes so as to adjust the assembled lining to the size of fireplace desired. A further object of the invention is to incorporate in the lining a hinged cover plate which may serve as a damper and convenient means for adjusting the same. A further feature of the invention is the providing of vertical and horizontal beads on the inside of the lining for reinforcing purposes as well as for the purpose of effecting a more thorough burning of the gases. Other objects and advantages of my device 35 will appear as the specification proceeds.

The preferred form of my invention is shown in the accompanying drawing in which Figure 1 represents a vertical section through the device along line 1—1 of Figure 2, Figure 2 a front view of the device, Figure 3, a horizontal section through the same along line 3—3 of Figure 2, Figure 4, an enlarged sectional detail view of a front edge of one of the side sections, Figure 5, an enlarged sectional detail view of a sliding engagement between the rear edge of a side section and the rear section, Figure 6 a sectional detail view illustrating the operating mechanism for the damper, Figure 7 a perspective detail view of a portion of the damper operating mechanism and Figure 8 a front view of a tube through which a chain operating the damper passes. While I have shown only the preferred form on the invention I wish

to have it understood that various changes or modifications may be made within the scope of the claims hereto attached without departing from the spirit of the invention.

My fireplace lining (1) is preferably made of four sections, including the left hand section (2) the right hand section (3) a central section (4) and a top (6). The two side sections (2 and 3) are symmetrical in form and are curved to follow the outlines of the fireplace. They cover the sides of the fireplace and extend rearwardly to cover a large portion of the back of the fireplace. At the latter end they terminate in grooves (7) adapted to slidably engage with the center piece (4). At the front end they are provided with suitable flanges (8) adapted to engage the edge of the fireplace brick work. These side sections are preferably made of standard size and to render my lining available for different sized fireplaces I provide the central section (4) which may be made in different widths while conforming in length and in shape to the inner edges of the side sections. The lower portion of the three sections thus far described is preferably beaded up to a height of about two feet in a manner shown in Figures 1 and 2; the beads (10) serving as reinforcing members for the metal plates and being adapted to arrest the upward motion of the inflammable gases and to thereby promote a more complete combustion of the same. For the purpose of firmly holding the three sections in place I provide in suitable places perforated lugs (9) on the back of the same which may be engaged by wires (11) worked into the brickwork.

The tops of the three sections thus far described are shaped to form a slanting seat for the top plate (6) which latter is hingedly secured at the lower and forward ends of the supporting plates, semi-circular bearings (12) engaging corresponding seats (13) in the plates. Projections (14) on the front edges of the two side sections prevent the bearings from slipping off their seats. The top plate serves as a damper and its position may be adjusted by means of the arrangement shown in detail in Figures (6, 7 and 8). A lug (16) rising from the central portion of the top plate is provided with a perforation (17) adapted to be engaged by a flat link chain 18 extending through a tube (19) embedded in the front wall (21) of the

fireplace. To facilitate the handling of the chain a ring (22) is provided at its front end and a roller (23) between two ears (24) at the rear end of the tube. The front end 5 of the tube is threadedly engaged by a flange member (25) provided with a small slot (26) adapted to engage a link of the chain for holding the same and the top plate in any desired position. A hole (27) is provided 10 in each side section to promote circulation of air behind the lining.

Claims:

1. In a metal fireplace lining, a right and a left side section each curved to also form 15 a portion of the back of the fireplace with their edges spaced in confronting relation, and a central back section connecting said edges in vertical grooved engagement.
2. In a metal fireplace lining, a right and 20 a left side section each curved to also form a portion of the back of the fireplace with their edges spaced in confronting relation, and a central back section connecting said edges in vertical grooved engagement, the 25 three sections being cut on top to a single plane slanting downwardly toward the front of the fireplace, and a damper cover thereover resting thereon and pivoted to the two front corners of the two side sections.
3. In a metal fireplace lining, a right and 30

a left side section each curved to also form a portion of the back of the fireplace with their edges spaced in confronting relation, and a central back section connecting said edges in vertical grooved engagement, the 35 three sections being cut on top to a single plane slanting downwardly toward the front of the fireplace, a damper cover thereover resting thereon and pivoted to the two front corners of the two side sections, and means 40 above said cover for opening it.

4. In a metal fireplace lining, a right and a left side section each curved to also form a portion of the back of the fireplace with their edges spaced in confronting relation, 45 and a central back section connecting said edges in vertical grooved engagement, said sections having a cellularly disposed interiorly ribbed surface.

5. In a metal fireplace lining, a right and 50 a left side section each curved to also form a portion of the back of the fireplace with their edges spaced in confronting relation, and a central back section connecting said edges in vertical grooved engagement, said 55 sections having a plurality of vertical and cross ribs projecting from their inner surfaces forming a series of non-communicating heat deflecting pockets.

ALBERT H. SANDSTROM.
